NECKTIE SUPPORT OR SIMILAR ARTICLE

Albert Leebow, East Rockaway, N. Y., assignor to Berkeley Industries, Jersey City, N. J., a corporation of New Jersey

Application January 18, 1949, Serial No. 281

Term of patent 14 years

(Cl. D33—8)

To all whom it may concern:

Be it known that I, Albert Leebow, a citizen of the United States and a resident of East Rockaway, New York, have invented a new, original, and ornamental Design for a Necktie Support or Similar Article, of which the following is a specification, reference being had to the accompanying drawing, forming a part thereof, in which

Figure 1 is a side elevational view of a necktie support, or similar article, showing my new design; and

I claim:

The ornamental design for a necktie support or similar article, as shown.

ALBERT LEEBOW.
